FREDERICK F. ZEIER AND CLARENCE C. SMITH, OF CHICAGO, ILLINOIS, ASSIGNEES TO UNION SPECIAL MACHINE COMPANY, OF CHICAGO, ILLINOIS, A CORPORATION OF ILLINOIS

DIFFERENTIAL FEEDING MECHANISM FOR SEWING MACHINES

Application filed November 5, 1930. Serial No. 493,648.

The invention relates to new and useful improvements in a sewing machine and more particularly to a feeding mechanism for giving a differential movement to the feed dogs.

5 An object of the invention is to provide a differential feeding mechanism wherein the feed bar carrying the auxiliary feed dog is mounted for reciprocation in supporting bearings spaced from each other and is moved back and forth therein by a connection attached to the feed bar between said supporting bearings.

A further object of the invention is to provide a feeding mechanism of the above type wherein the feed bar supporting bearings are in the form of sleeves and the feed bar is circular in cross section and wherein means independent of the bearings is provided for holding said feed bar to a right line back and forth movement.

25 A further object of the invention is to provide a feeding mechanism of the above type wherein the feed dog is secured to the feed bar at a point adjacent one of the supporting bearings for the feed bar and wherein the means which holds the feed bar to a right line movement is disposed at a distance therefrom so that the wear of the parts in either instance has little effect on the movements of 30 the feed dog back and forth.

A still further object of the invention is to provide a feeding mechanism of the above type wherein the feed bar is made hollow so as to reduce the weight thereof to a minimum.

35 These and other objects will in part be obvious and will in part be hereinafter more fully disclosed.

In the drawings which show by way of illustration one embodiment of the invention:

40 Fig. 1 is a view partly in section and partly in plan showing a portion of a sewing machine having the improvements applied thereto.

45 Fig. 2 is an enlarged view partly in section

and partly in side elevation showing the improved feeding mechanism.

Fig. 3 is a view of the same from the rear of the machine and showing a portion of the work support.

50 Fig. 4 is a sectional view on the line 4, 4, of Fig. 1.

The invention is directed to a feeding mechanism for sewing machines which is provided with a main feed dog operating on the material in rear of the needles and an auxiliary feed dog operating on the material in advance of the needles. This auxiliary feed dog is mounted on a feed bar which is in the form of a sleeve circular in cross section. The feed bar is made in sleeve form so as to reduce its weight and still afford a substantial bearing surface for the feed bar. The feed bar is mounted for reciprocation in two sleeve bearings formed integral with the main feed bar. 55 There is a sleeve mounted on this auxiliary feed bar which is located between the bearings and a link is connected to the sleeve for moving the feed bar back and forth. The sleeve is provided with a projecting arm, the 60 outer end of which slides freely back and forth between two spaced guide bars and this holds the feed bar so that the feed dog will have a movement in a vertical plane.

65 Referring more in detail to the drawings, 75 the invention is shown as applied to a sewing machine which includes a supporting bed 1 provided with the usual standard 2 carrying the overhanging arm and the needle. Mounted in this bed is a main actuating shaft 3. 80 The parts of the stitching mechanism and thread controllers, shown more or less diagrammatically in Fig. 1 of the drawings, have not been described as they form no part of the present invention.

85 The present invention has to do with a feeding mechanism which includes a main feed dog 5 and an auxiliary feed dog 6. The main feed dog 5 is carried by a feed bar 7 which extends rearwardly and is provided 90

with a sleeve 8 freely connected to a rod 9 carried by the feed rocker 10 and secured thereto by screws 10^a, 10^b. The feed rocker carries a sleeve 9^a which is integral therewith. 5 A link 11 is provided with a collar 11^a which surrounds the sleeve 9^a and is secured thereto by screws 11^b, 11^c. This link is connected to the crank 12 carried by the main shaft 3. Thus it is that the feed rocker is oscillated and the feed bar 7 moved back and forth.

10 The feed bar carries a depending arm 13 which extends beneath the shaft 3. An eccentric strap 14 cooperates with an eccentric 15 on the main shaft and is pivoted at 16 to the arm 13. As the shaft oscillates the eccentric strap will raise and lower the forward end of the feed bar and give to the feed dog its rising and falling movements. The auxiliary feed dog 6 is carried by the feed bar 17. This feed bar 17 is circular in cross 15 section and is hollow as indicated at 18 in Fig. 4 of the drawings. This makes a very light feed bar which has sufficient surface in order to provide ample bearing support for the auxiliary feed bar. The feed bar 7 is provided with two sleeve bearings 19 and 20. The bearing 20 is located very close to the head 21 on the forward end of the auxiliary feed bar to which the auxiliary feed dog 6 is 20 attached. Said auxiliary feed dog is attached to the head 21 by a screw 22 and a ribbed connection so that it may be readily adjusted vertically and held from tilting or angular movement on the auxiliary feed bar. 25 Located on this auxiliary feed bar 17 intermediate the bearings 19 and 20 is a sleeve 23 which is secured to the feed bar by means of set screws 24. This sleeve carries a laterally projecting stud 25. The feed rocker 10 is 30 provided with an upstanding bracket arm 26 provided with a slot 27. A stud 28 is adjustable in the slot and clamped in an adjusted position by a nut 29. This stud projects to the inner side of the arm and is headed so as 35 to be firmly clamped in the bracket arm. A link 30 is provided with a sleeve 31 at the rear end thereof adapted to engage the stud 28. A sleeve 32 at the other end of the link 30 is 40 adapted to engage the stud 25. These two studs 25 and 28 projecting as they do in opposite directions maintain their connection with the link without the link being fastened thereto. As the feed rocker 10 oscillates it 45 will through the link 30 cause the auxiliary feed bar 17 to slide back and forth in the sleeve bearings 19 and 20. Thus it is that the auxiliary feed dog is moved back and forth. As this auxiliary feed bar is mounted 50 in bearings carried by the main feed bar, both feed bars will be raised and lowered by the eccentric 15.

The sleeve 23 is provided with a projecting arm 33 which extends through a slot 34 in the main feed bar. At the face of the main 55 feed bar opposite the auxiliary feed bar are

guide bars 35, 35 which are spaced from each other and are secured to the main feed bar by screws 36, 36. These bars are so placed that the end 37 of the arm 33 makes a fairly close sliding contact with these guide bars. The 70 guide bars are of sufficient length so that the head 37 is in contact with the guide bars throughout the entire movement given to the auxiliary feed bar which is in excess of the movement given to the main feed bar. In 75 other words, as the feed rocker oscillates, the main feed bar will be given a certain back and forth movement which is imparted to the main feed dog. The auxiliary feed bar is moved by its separate and independent connection to the feed rocker to a greater or less extent than the main feed bar. For fulling in the fabric in advance of the needle it will be given a greater stroke and for imparting a drag or stretching action to the fabric 80 it will be given a less stroke. It may be given the same stroke if the link is properly adjusted on the bracket arm on the feed rocker.

85 From the above it will be noted that the auxiliary feed dog is attached to the auxiliary feed bar at a point adjacent and very close to the supporting sleeve 20 so that any wear between the sleeve and the auxiliary feed bar will have very little effect in changing the path of the movement of the auxiliary feed dog. The sleeve is attached to the auxiliary feed bar between the two supporting bearings therefor, and consequently the auxiliary feed bar will be given its movement which is independent of the movement imparted to the main feed bar in a positive manner which imparts little or no lateral or side strains to the auxiliary feed bar. The auxiliary feed bar may be readily shifted in this sleeve, both endwise and angularly, for positioning the auxiliary feed dog relative to the needles, and to compensate for any inaccuracies in manufacture, and insuring that the feed dog be set with its feed surface horizontal. The 90 arm projecting laterally from the sleeve and making contact with the guide bars at some distance from the auxiliary feed bar, holds said feed bar to a right line movement on the main feed bar and also prevents any lateral 95 tilting of the auxiliary feed dog. Any wear between this arm and the guide bars will have little or no effect on this right line movement of the auxiliary feed bar and the plane of movement of the auxiliary feed dog.

100 It will be obvious that minor details in the manner of construction and the arrangement of parts may be made without departing from the spirit of the invention as set forth in the appended claims.

105 Having thus fully described the invention, what is claimed as new is desired to be secured by Letters Patent is:

110 1. A feeding mechanism for sewing machines comprising a main feed bar, a main feed dog carried thereby, a feed rocker to 115

which said main feed bar is connected, means for raising and lowering the feed bar, spaced bearing members carried by said main feed bar, a single auxiliary feed bar mounted in said bearings, an auxiliary feed dog carried thereby, means connected to said auxiliary feed bar between said supporting bearings for imparting a differential feeding movement to said auxiliary feed dog and means for holding said auxiliary feed bar to a right line movement on said main feed bar.

2. A feeding mechanism for sewing machines comprising a main feed bar, a main feed dog carried thereby, a feed rocker to which said main feed bar is connected, means for raising and lowering the feed bar, spaced bearing members carried by said main feed bar, a single auxiliary feed bar mounted in said bearings, an auxiliary feed dog carried thereby, a sleeve carried by said auxiliary feed bar and disposed intermediate said supporting bearings, a link connected to said sleeve and to the feed rocker for imparting a differential feeding movement to said feed bar and means for holding said auxiliary feed bar to a right line movement on said main feed bar.

3. A feeding mechanism for sewing machines comprising a main feed bar, a main feed dog carried thereby, a feed rocker to which said main feed bar is connected, means for raising and lowering the feed bar, spaced bearing members carried by said main feed bar, a single auxiliary feed bar mounted in said bearings, an auxiliary feed dog carried thereby, means connected to said auxiliary feed bar between said supporting bearings for imparting a differential feeding movement to said auxiliary feed dog, said auxiliary feed bar being circular in cross section and means independent of its supporting bearings for holding said auxiliary feed bar to a right line movement on said main feed bar.

4. A feeding mechanism for sewing machines comprising a main feed bar, a main feed dog carried thereby, a feed rocker to which said main feed bar is connected, means for raising and lowering the feed bar, spaced bearing members carried by said main feed bar, an auxiliary feed bar mounted in said bearings, an auxiliary feed dog carried thereby, a sleeve carried by said auxiliary feed bar and disposed intermediate said supporting bearings, a link connected to said sleeve and to the feed rocker for imparting a differential feeding movement to said feed bar, an arm attached to said sleeve, guide bars between which the end of said arm reciprocates for holding said auxiliary feed bar to a right line movement on said main feed bar.

5. A feeding mechanism for sewing machines comprising a main feed bar, a main feed dog carried thereby, a feed rocker to which said main feed bar is connected, means

for raising and lowering the feed bar, spaced bearing members carried by said main feed bar, a hollow auxiliary feed bar circular in cross section having a sliding fit with said bearings, a sleeve attached to said auxiliary feed bar intermediate said bearings, means attached to said sleeve for imparting a differential feeding movement to said auxiliary feed bar, an auxiliary feed dog carried by said bar, and means for holding said auxiliary feed bar to a right line movement in said bearings.

6. A feeding mechanism for sewing machines comprising a main feed bar, a main feed dog carried thereby, a feed rocker to which said main feed bar is connected, means for raising and lowering the feed bar, spaced bearing members carried by said main feed bar, a hollow auxiliary feed bar circular in cross section having a sliding fit with said bearings, a sleeve attached to said auxiliary feed bar intermediate said bearings, means attached to said sleeve for imparting a differential feeding movement to said auxiliary feed bar, an auxiliary feed dog carried by said bar, means for holding said auxiliary feed bar to a right line movement in said bearings, said sleeve being adjustably secured to said auxiliary feed bar whereby said auxiliary feed bar may be shifted to different set positions.

7. A feeding mechanism for sewing machines comprising a main feed bar, a main feed dog carried thereby, a feed rocker to which said main feed bar is connected, means for raising and lowering the feed bar, spaced bearing members carried by said main feed bar, a hollow auxiliary feed bar circular in cross section having a sliding fit with said bearings, a sleeve attached to said auxiliary feed bar intermediate said bearings, means attached to said sleeve for imparting a differential feeding movement to said auxiliary feed bar, an auxiliary feed dog carried by said bar, means for holding said auxiliary feed bar to a right line movement in said bearings, said last named means including an arm projecting from said sleeve and guide bars between which the end of said arm reciprocates.

8. A feeding mechanism for sewing machines comprising a main feed bar, a main feed dog carried thereby, a feed rocker to which said main feed bar is connected, means for raising and lowering the feed bar, spaced bearing members carried by said main feed bar, a hollow auxiliary feed bar circular in cross section having a sliding fit with said bearings, a sleeve attached to said auxiliary feed bar intermediate said bearings, means attached to said sleeve for imparting a differential feeding movement to said auxiliary feed bar, an auxiliary feed dog carried by said bar, means for holding said auxiliary feed bar to a right line movement in said

- bearings, said last named means including an arm projecting from said sleeve, guide bars between which the end of said arm reciprocates, said bars being disposed at a distance from said auxiliary feed bar.
- 5 9. A feeding mechanism for sewing machines comprising a main feed bar, a main feed dog carried thereby, a feed rocker to which said main feed bar is connected, means for raising and lowering the feed bar, spaced bearing members carried by said main feed bar, a single auxiliary feed bar mounted to slide freely in said bearings, an auxiliary feed dog attached to said feed bar and located adjacent one of said bearings, means attached to the said auxiliary feed bar intermediate said bearings for imparting a differential movement to the auxiliary feed dog and means for holding said auxiliary feed bar to a right line movement in said supporting bearings.
- 10 15 20 25 30 35 40 45 50 55 60 65 70 75 80 85 90 95 100 105 110 115 120 125 130
10. A feeding mechanism for sewing machines comprising a main feed bar, a main feed dog carried thereby, a feed rocker to which said main feed bar is connected, means for raising and lowering the feed bar, spaced bearing members carried by said main feed bar, an auxiliary feed bar mounted to slide freely in said bearings, an auxiliary feed dog attached to said feed bar and located adjacent one of said bearings, means attached to the said auxiliary feed bar intermediate said bearings for imparting a differential movement to the auxiliary feed dog, means for holding said auxiliary feed bar to a right line movement in said supporting bearings, said last named means including an arm fixed to said auxiliary feed bar and projecting therefrom and guide bars between which the end of said arm reciprocates.
11. A feeding mechanism for sewing machines comprising a main feed bar, a feed dog carried thereby, a feed rocker to which said main feed bar is connected, means for raising and lowering the feed bar, a supporting means carried by said main feed bar, a single auxiliary feed bar mounted in said supporting means for endwise movement independent of the main feed bar, an auxiliary feed dog carried thereby, means connected to said auxiliary feed bar for imparting a differential movement to said auxiliary feed dog and means for holding said auxiliary feed bar to a right line movement on said main feed bar.
12. A feeding mechanism for sewing machines comprising a main feed bar, a feed dog carried thereby, a feed rocker to which said main feed bar is connected, means for raising and lowering the feed bar, a supporting means carried by said main feed bar, a single auxiliary feed bar mounted in said supporting means for endwise movement independent of the main feed bar, an auxiliary feed dog carried thereby, a sleeve rigidly attached to said auxiliary feed bar, means connected to said sleeve for imparting a differential feeding movement to said auxiliary feed dog, means carried by said sleeve and cooperating with said feed bar for holding said auxiliary feed bar to a right line movement on said main feed bar.
- In testimony whereof, we affix our signatures.
